EDWARD W. BRACKENBURY, OF MILWAUKEE, WISCONSIN, ASSIGNOR TO THE T. L. SMITH CO., OF MILWAUKEE, WISCONSIN, A CORPORATION OF WISCONSIN.

MACHINE FOR MIXING TAR MACADAM.

1,010,114.

Specification of Letters Patent. Patented Nov. 28, 1911.

Application filed June 8, 1910. Serial No. 565,685.

To all whom it may concern:

Be it known that I, EDWARD W. BRACKENBURY, a subject of the King of England, residing at Milwaukee, in the county of Milwaukee and State of Wisconsin, have invented a new and useful Improvement in Machines for Mixing Tar Macadam, of which the following is a specification.

My invention relates to machines to be used in street paving, and in that kind of paving in which a concrete base is laid first and is subsequently covered by a tar macadam, or bithulithic surface; and the objects of my invention are, first, to provide portable means for expeditiously drying and heating the stone for the mixture; second, to provide means for efficiently mixing the tar or bituminous ingredient with the stone while keeping the mixture hot, and to provide adequate means for feeding and discharging the machine. I attain these objects by the mechanism illustrated in the accompanying drawing, which forms a part of this specification, and in which—

25 Figure 1 is a side view of the complete machine, and Fig. 2 is an end view of same.

In the drawing I have shown a standard batch concrete mixer of the tilting type, mounted on a truck and furnished with a steam engine and boiler for motive power.

30 10 is the mixer drum of a well known form, which is rotated to mix and tilted to discharge as usual.

35 Numeral 31 designates the mixing blades which are secured to the drum on its interior.

11 is the feed spout through which material is introduced to the drum. Any loading device actuated by power may be substituted for this feed spout, which is shown 40 only as a conventional representation of a feeding means.

12 is the boiler, provided with the smoke stack 13. Connected with this smoke stack is a laterally projecting conduit 14, which 45 is continued in a portion 15 extending longitudinally of the truck frame. This portion 15 is supported on curved stanchions 16. The end of the conduit 15 is loosely connected to the part 17, so that the latter may 50 swing on 15 as a center. The lower end of the pipe 17 is provided with a plate 18, which abuts the discharge end of the drum 10. The end of the pipe 17 is also provided 55 with a horizontally extending bar 19 clamped to the pipe, the ends of this bar be-

ing pivotally connected to arms 20 which are pivotally connected to a tilting part of the mixer frame as at 21. A turn buckle 22 is provided in each arm 20, whereby the length of the arm may be nicely adjusted. 60

23 are bolts or other similar means connecting 17 and 15, but placed in circumferential slots in one part or the other to allow the swinging movement of 17.

It is obvious that as the mixer drum 10 65 is tilted to discharge, the pivotal connection 21 will swing in an arc around the trunnions 24, and the arms 20 will swing the pipe 17 and plate 18 entirely clear of the discharge end of the mixer drum. Also 70 whenever the drum 10 is in its horizontal position the pipe 17 will be in direct communication with the interior of the drum.

25 and 26 are dampers or valves in the smoke stack 13 and lateral conduit 14 respectively. By means of these dampers or valves the products of combustion from the boiler firebox may be directed up the smoke stack or through the conduits 14, 15 and 17 to the mixer drum 10 whence they will pass 80 off through the feed spout 11.

In the practical operation of mixing tar macadam the stone and screenings for one batch is fed to the drum, valve 26 is opened and valve 25 is partly or wholly closed as 85 the necessities of the case may require. The products of combustion will fill the drum maintaining a temperature of about 600 degrees F. therein. As the drum revolves the contained stone and screenings will be lifted 90 by the mixing blades of the drum and will be almost continually falling through the hot gases of combustion. The contained materials will thus be rapidly heated, much more rapidly than while lying still in an 95 oven. As soon as the stone is hot and dry the tar or other bituminous substance is introduced through the feed spout 11 and will be thoroughly mixed with the hot stone and screenings by the continuous rotation of 100 the drum. The mixture is discharged by tilting the drum as usual, the pipe 17 swinging outward away from the discharge opening of the drum as the latter starts its tilt- 105 ing movement.

By removing the bolts 23 and the radius bars 20, the pipe 17 may be removed, and the machine may then be used as an ordinary concrete mixer for laying the first course of the pavement.

2

While the machine is being used as a concrete mixer the exhaust of the engine in the stack materially aids the draft for the fire in the boiler fire box. When the products of combustion are being passed through the mixer drum however the draft is deprived of the assistance of the exhaust and I therefore provide a steam jet from the nozzle 28 to force air through the inlet 27 under the fire. Valve 30 in the pipe 29 controls this steam jet.

Of course the steam jet blower shown might be substituted by a fan blower driven from the engine shaft.

15 What I claim as my invention and desire to secure by Letters Patent is:

1. In a machine for mixing tar macadam a rotatably mounted mixing drum, means for feeding material to said drum through one end thereof, means for tilting said drum to discharge through its other end, a pipe in communication with said drum through the discharge end thereof when the drum is in mixing position and also in communication 25 with a source of heated gases, means for rotating said drum continuously and means for swinging a part of said pipe as the drum is tilted to afford a free discharge of the material.
2. In a machine for mixing tar macadam, a rotatably mounted mixing drum, means for feeding said drum through one end thereof and discharging it through the other end thereof, a steam engine and boiler affording 30 means for rotating said drum, a pipe adapted to convey the products of combustion of the boiler fire to the interior of the mixing

drum through the discharge end thereof, a joint in said pipe allowing part of the pipe to swing relatively to the other part, means 40 for swinging said pipe clear of the drum, and means for forcing the fire and directing the heated gases to the mixing drum or to the atmosphere.

3. A mixing machine comprising a mixing 45 drum rotatably mounted in a tiltable frame, an attachment fitting against the discharge end of the drum when it is in mixing position, said attachment being swingingly supported from the machine frame, and rods 50 pivotally attached to said swinging attachment and also to the tiltable frame at a point considerably above the center on which said frame swings, whereby as the drum is tilted the attachment is swung outward from the 55 drum end, and while the mixer is in mixing position the attachment is held in position against the end of the drum.

4. In a machine for mixing tar macadam a rotatable mixing drum, means for feeding 60 material to one end of said drum and for discharging it through the other end thereof, a pipe adapted to convey heated gases attached to a source of such gases at one of its ends, the other end of said pipe adapted 65 to be held against, and to communicate with, the drum through the discharge end thereof, and means for automatically moving said pipe away from said drum by the discharge operating mechanism.

EDWARD W. BRACKENBURY.
